FASTENER FOR GUARD FENCES

William Blackmore, Sharon, Pa., assignor to
 National Malleable and Steel Castings Company,
 Cleveland, Ohio, a corporation of Ohio

Application January 24, 1931, Serial No. 510,863

8 Claims. (Cl. 248—31)

My invention is directed to highway fence protection of the type in which the cables, wire ropes, pipes or rods, etc., of which the fence is formed, are supported by a series of posts, and relates particularly to means for supporting the fencing in such position that it will be held away from the posts and toward the roadway, so as to minimize the damage which may be done to either fence or motor vehicle when the former is struck by the latter. My invention provides fasteners or supports for the fencing by which the fencing is not only spaced inwardly from the post such a distance that the wheels and other parts of motor vehicles will be prevented from coming in contact with the post, but it also prevents the parts of such vehicles from striking protruding parts of the clamp or fence support. My improved construction is so arranged that if a vehicle strikes the fencing, it will slide past the post and fence support thereon without material injury to it or to them.

In the accompanying drawings Figure 1 shows a miniature elevation of a guard fence post to which fencing in the form of cables is secured by fasteners or supports embodying my invention; Figure 2 is a side elevation of one of the supports showing the cable in position therein; Figure 3 is a plan thereof and Figure 4 is a front elevation thereof; Figure 5 is a side elevation of the securing bolt and Figure 6 is an end elevation thereof; Figure 7 is a partial assembly in side elevation of a modified form of my improved support; Figure 8 is a complete assembly in vertical section thereof; Figure 9 is a side elevation somewhat similar to a portion of Figure 2, but showing a modification thereof; and Figure 10 is a plan of such modified structure otherwise similar to a portion of Figure 9.

Referring more particularly to the accompanying drawings, the supporting posts are indicated at A and the protection members which I have shown in the form of wire cables at B. My improved supporting mechanism consists in a metal mounting or support 2 preferably made in the form of a casting, which has sharpened projections 3 adapted to sink into the post A and thus keep the support 2 from shifting relative thereto.

At its end away from the post A the support is provided with a recess 4, which receives the protection member B. The lower portion of the recess is struck on an arc of a circle from its outer lip 5 toward the rear of the recess and forms a stationary receiving jaw 6 for the cable B. The jaw 6 preferably has upwardly extending teeth 7 which are intended to engage the member B and

prevent it from slipping with respect to the support. The support 2 has an aperture 8 preferably extending centrally and horizontally therethrough for reception of the shank portion 9 of the bolt 10, which extends through a corresponding hole 11 in the post and in which it is intended to be held by the nut 12 which is threaded onto the rear end of the shank and engages the rear side of the post A. The bolt 10 at its forward end has an offset jaw portion 13 with an arc-shaped inner face terminating in an outer lip 14 oppositely facing the lip 5. The jaw 13 preferably has a series of teeth 15 which project radially inwardly and are intended when the bolt 10 is assembled in the support to face the teeth 7 of the support 2. The walls of the inner portion of the recess 4 have inclined faces 8a which merge into the walls of the through aperture 8.

The aperture 8 preferably is of a diameter but slightly larger than the bolt shank 9, so as to provide metal around the rod at the rear of the support so that a slight movement of the support will put the bolt into shear, which thus affords a reinforcement for the support against lateral blows.

In assembling the cable or other protection member B and the fastening on a post A, the support 2 is placed in position with its aperture 8 in alignment with the hole 11 in the post A and the shank 9 of the bolt 10 is then inserted therethrough and the nut 12 applied on the threaded rear end of the shank, but without being tightly turned down. The member B is then slipped in between the stationary jaw 6 on the support and the movable jaw 13 on the bolt 10 and then the nut 12 is set up tightly, thus causing the jaws 6 and 13 and the teeth 7 and 15 to grip the member B and the support 2 to be drawn back against the post A, thus embedding the projections 3 in the sides of the post. Also, as the jaw 13 is drawn inwardly, its upper side engages the inclined wall 8a, as is shown in Fig. 2, and is thus caused to bite strongly down upon the cable or other protection member.

In Figures 7 and 8 I have shown a modified form of my invention, in which the lips 25 at the upper and lower edges of the recess 24 are symmetrical and the bolt 30 has both of the fence member receiving jaws 26 formed upon it. The shank adjacent the jaws is slit so as to permit the jaws to be drawn together or spread apart. Each of these jaws 26 is preferably formed with inwardly projecting teeth 27 thereon. It will be seen that as the bolt 30 is pulled in through the support by the nut 32, the tapered surfaces 110

33 in the central aperture will cause the split portions of the shank 29 to be drawn together and clamp the jaws 26 and the teeth 27 thereon inwardly upon the cable or other member. Preferably the bolt 30 is made of two separate forgings which are spot welded together.

In Figures 9 and 10 I have shown a further modification of my invention in which the jaws 40 and 41 hold the cable or other protection member in such manner as to permit it to slide freely with respect to the support. I accomplish this by providing means for preventing the jaws from being clamped tightly upon the cable. Such means preferably consists in forming a depression 42 in the rear surface of the movable jaw 41 in which a shoulder 43 projecting from the surface of the recess 44 is intended to bear.

It will thus be seen that as the bolt is pulled rearwardly the vertical wall of the depression 42 will engage the shoulder 43 and thus limit the inward movement of the jaw 41 and its clamping effect on the cable or other member. Hence, if the clearance between the jaws 40 and 41 is properly adjusted, they will support the cable or other member and yet permit it to slide freely with respect to the fasteners.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. A fence fastening for a highway guard post comprising a support having an aperture therethrough and a fence element receiving jaw, a bolt having a shank extending through the aperture in the support and comprising means for securing the support to a post, said bolt having also a fence element engaging jaw movable vertically and adapted to engage a fence element on the side opposite to the jaw on the support.
2. A fence fastening for a guard fence post comprising a support having an aperture therethrough and a fence element receiving jaw, a bolt having a shank extending through the aperture in the support and comprising means for securing the support to a post, said bolt having also a jaw for engaging a fence element on the side opposite to the jaw on the support, said aperture having a sloping wall adapted to be engaged by said bolt jaw to force the latter into firmer engagement with the fence element upon inward movement of the bolt, the fence element when clamped within said jaws extending outwardly from the post at least as far as any portion of the support and the bolt.
3. A fence fastening for a guard fence post comprising a support having a recess therethrough having an enlarged outer portion, an arc-shaped surface in said enlarged portion forming a fence element receiving jaw, a member having a shank extending through said recess and having at the rear end means for se-

curing to a post, said member also having a fence element engaging jaw seating in said enlarged portion oppositely disposed to the fence element receiving jaw, and coacting means on said support and member for moving said jaws together.

4. A fence fastening for a highway guard post comprising a support having a recess therethrough having an enlarged outer portion, a surface in the enlarged portion forming a fence element receiving jaw, a member having a shank extending through said recess, and an offset jaw seating in the enlarged portion of the recess forming a fence element engaging jaw opposite the fence receiving jaw, said jaws being movable vertically relative to each other and coacting means on said support and member for limiting said relative vertical movement, said member also comprising means for securing the support in operative relation to a post.

5. A fence fastening for a highway guard post comprising a support having a recess with an enlarged forward portion and a reduced rearward portion extending horizontally through the support, a member having a pair of oppositely disposed fence element receiving jaws thereon and a rearwardly extending shank intended for seating respectively in the enlarged outer portion and reduced rearward portion of the recess, said member also comprising means for clamping the jaws tightly on a fence element and for securing both support and member to a post.

6. A fence fastening for a highway guard post comprising a support having a recess with an enlarged forward portion and a reduced rearward portion extending horizontally through the support, a member having a pair of oppositely disposed fence element receiving jaws thereon and a rearwardly extending shank intended for seating respectively in the enlarged outer portion and reduced rearward portion of the support, means for drawing the member inwardly relative to the support, and tapered surfaces in the recess in the support for causing the jaws to clamp tightly upon a fence element as the member is drawn rearwardly relative to the support.

7. A fence fastening for a highway guard post comprising a pair of fence element clamping jaws, means for supporting the jaws in horizontal spaced relation to a post, means for retracting at least one of the jaws relative to the supporting means, said supporting means having an inclined surface in engagement with one of the jaws for forcing the said jaws to grip a fence element tightly.

8. A fastening for a guard fence post comprising a pair of fence member holding jaws, means for supporting the jaws in horizontal spaced relation to the post, means for adjusting the jaws toward and away from each other by relative horizontal movement to receive and support a fence member, and means for limiting the horizontal movement of the jaws to permit endwise movement of the fence member between the jaws.

WILLIAM BLACKMORE.
